ATTORNEY'S.

UNITED STATES PATENT OFFICE.

FRANK H. DILLON, OF ROCK ISLAND, ILLINOIS.

SMOKE CONSUMER.

Application filed August 30, 1920. Serial No. 406,824.

To all whom it may concern:

Be it known that I, FRANK H. DILLON, a citizen of the United States, residing at Rock Island, in the county of Rock Island 5 and State of Illinois, have invented certain new and useful Improvements in Smoke Consumers, of which the following is a specification.

My invention relates to improvements in 10 devices for burning or consuming the smoke in steam boilers and furnaces and for economizing on fuel used therein, in which jets of air are introduced into the fire box above the level of the grate bars and the fuel there- 15 on through curved pipes mounted at the sides of the boiler or furnace and extending into the combustion chamber from above, or in the case of boilers of the fire box type having water legs on each side of the fire 20 chamber, the air pipes conduct the air into the fire chamber through draft tubes secured in the water legs of the boiler.

The objects of my invention are; first, to 25 provide means for regulating the amount of air introduced into the fire chamber which can be applied to the ordinary form of tubular boilers, to water tube boilers and to fire box boilers including locomotive boilers having a water leg on each side of the fire chamber or to any other form of boiler or furnace in which a down draft or horizontal draft of air is injected into the fire chamber by the use of steam, compressed air or other fluid; second, to provide positively operated 30 means for closing the air draft for such boilers and furnaces operating independently of the steam or compressed air valves.

I attain these objects by the mechanism 35 illustrated in the accompanying drawings, in which—

Figure 1 is a front elevation of a boiler furnace with my device applied thereto. the righthand side of the drawing showing 40 boiler furnace with the front plate and air valves removed.

Figure 2 is a plan view of my device as 45 shown in Figure 1, but showing the left middle manifold in section on the line xx of Figure 1 with the steam jets and air valves removed, and the right middle manifold in section on the line xx of Figure 1.

Figure 3 is a sectional elevation of my device applied to a firebox boiler of the water leg type with bricked-in installation.

Figure 4 is a side elevation of my device 55 showing air tubes, stationary and movable plates in dotted lines in the left portion of the figure and showing the right portion of the figure in section.

Figure 5 is a sectional detail of the air 60 valves, etc.

Similar numerals refer to similar parts throughout the several views.

Air tubes, 2, are provided at each side of the ordinary tubular boilers as in Figure 1 65 or air tubes, 21, as shown in Figure 3. The upper ends of these air tubes are slightly enlarged to seat in bosses, 4^b, formed in a stationary plate, 4, which is mounted upon the brickwork of the ordinary bricked-in boiler 70 installation or suitably secured at the desired height by any of the well-known means in the case of other boilers. This stationary plate is provided with a series of circular openings, 4^a, corresponding to the interior of the tubes, 2 and 21. Similar openings, 10^a, are formed in the movable plate, 10, which is slidably mounted upon the stationary plate, 4, in such a way as to slide longitudinally and secured in place by gravity or any other desired means. 75

An air admission manifold, 3, is secured to the sliding plate 10, so as to slide with the plate, 10. Steam jets, 7, are secured in the top of the manifold, 3, and may also be additionally secured by brackets, 9, riveted or bolted to the sliding plate, 10. Each jet, 7, is provided with an air valve, 8, mounted thereon which is secured to the jet by a set screw, 8^b, passing through a collar, 8^a, or by 85 any other suitable means which will allow the valve, 8, to be adjusted vertically upon the jet, 7. The upper ends of the jets are secured to and open into a supply pipe 5, which may be one continuous pipe or sections of pipe connected by Ts, 6, as in Figure 4. 90

The pipe, 5, is supplied with steam through the pipe, 19, which may be connected with the boilers in any suitable way, by 100 intermediate pipes, 14 and 15. Valves, 16 and 17, are provided by which the steam

supply may be shut off from the steam pipes on either side; and the valve, 18^a, is provided to shut off the steam in the pipe, 19.

In order to allow the pipe, 5, to move longitudinally with the manifold, 3, the connections at the elbows, 14^a, pipes, 15, and valves, 16 and 17, are so made as to allow for sufficient turning motion and where the length of the pipe, 14, is not sufficient to allow the necessary play, double elbows and connections may be used to connect pipe, 14, with pipe, 15.

I make no claim for any particular form of flexible or movable connection, as these 15 are well-known and in common use.

The manifold, 3, is preferably left open at the rear end, but the opening may be at either end or at the side or top without departing from the spirit of my invention.

20 In Figure 2 an air opening, 3^a, is shown in the top of the manifold.

When applied to water tube boilers, the air may be introduced into the fire chamber inside the furnace walls as in Figure 1, or 25 through a water leg as in Figure 3, or the air pipes may be mounted outside the furnace walls and extended through the furnace walls similarly to the arrangement shown in Figure 3, considering the furnace walls substituted for the water leg, 26.

30 The sliding plate, 10, is connected at one end by a suitable yoke, 11^b, and connecting rod, 11, to one end of a lever, 12, fulcrumed at 13^a, in any suitable support, 13, and the other end of the lever forms a handle, 12^a, by which same can be manually operated. The sliding plate, 10, and manifold, 3, can be moved longitudinally upon the stationary plate, 4, far enough to move the openings, 40 10^a, out of juxtaposition with the openings, 4^a, so that the intermediate portions of the sliding plate, 10, will securely close the upper end of the air tubes, 2 or 21.

45 In the operation of my device, the fires are built under the boilers in the usual way. As soon as sufficient steam pressure has been raised, steam may be turned into the pipes, 15, and passing out through the jets, 7, will carry air downward into the pipes, 2 or 21, as the case may be. This air will pass through the lower ends of the pipes, 2 or 21, into the fire chamber. The lower ends of the tubes, 2, are preferably curved inward to direct the stream of air somewhat toward the middle of the grates as well as downward and the same result as obtained by the nozzle, 25, shown in Figure 3.

50 In batteries of boilers, of course steam may be used from one boiler to assist in firing up other boilers.

In practice, a steam pressure of five pounds or upward will be found sufficient to operate my device effectively.

55 In practice, I find it is advisable to have means for positively closing entirely the up-

per ends of the air tubes. Even though the steam or compressed air is entirely shut off, if the air tubes are not thus closed, there will be a heavy inrush of air through them on account of the natural stack draft and when building a fire before any draft is established, it is sometimes necessary to close the upper ends of the air tubes to prevent smoke escaping from the furnace into the boiler room.

In practice, a very light steam pressure in the jets, 7, is sufficient to carry an ample supply of air to the fire chamber and it is necessary to provide means by which the supply of air can be limited while the air tubes 2 and 21 are left entirely open. In the smoke consumers heretofore in use, no provision has been made for adjusting the air supply except by limiting the supply of steam or sliding the plates and there is always a likelihood that the steam jets would be open too far so that too much air would be drawn into the tubes or the sliding plate would be moved in such a position as to prevent the entrance of the steam directly into the upper ends of the air tubes.

In my device, the air regulating valve prevents the admission of too much air even though the steam jet is opened wider than intended and ample means are provided for entirely closing the air tubes when desired.

The manifold, 3, may be built integral or with one side removable to allow access to the jets and regulating valves secured therein.

100 I claim:

1. In a smoke consumer, the combination with a stationary plate carrying air tubes secured thereto, of a movable plate mounted thereon, openings in the movable plate corresponding approximately in size to the upper ends of the air tubes, and air regulating valves suitably secured above the openings in the movable plate.

2. In a smoke consumer the combination with a series of air tubes suitably secured to discharge within a furnace, of a movable plate secured adjacent to the outer ends of the air tubes having openings corresponding in size and number to the air tubes and air valves suitably secured adjacent the openings.

3. In a smoke consumer, the combination with a stationary plate carrying air tubes secured thereto, of a movable plate mounted thereon, openings in the movable plate corresponding approximately in size to the upper ends of the air tubes, jet tubes mounted upon the movable plate in juxtaposition to the openings therein and air regulating valves secured to the jet tubes above the openings in the movable plate.

4. In a smoke consumer, the combination with a stationary plate carrying air tubes secured thereto, of a movable plate mounted

thereon, openings in the movable plate corresponding approximately in size to the upper ends of the air tubes, jet tubes mounted upon the movable plate in juxtaposition to the openings therein and air regulating valves suitably secured above the openings in the movable plate.

5. In a smoke consumer, the combination with a stationary plate carrying air tubes secured thereto, of a movable plate mounted thereon, openings in the movable plate corresponding approximately in size to the upper ends of the air tubes, jet tubes mounted upon the movable plate in juxtaposition to the openings therein, air regulating valves secured to the jet tubes above the openings in the movable plate and means for adjusting the height of the air regulating valves above the openings.

20 6. In a smoke consumer, the combination with a stationary plate carrying air tubes secured thereto, of a movable plate mounted thereon, a manifold mounted upon the movable plate, openings in the movable plate corresponding approximately in size to the upper ends of the air tubes, jet tubes mounted upon the movable plate in juxtaposition to the openings therein and air regulating valves secured to the jet tubes above the openings in the movable plate.

35 7. In a smoke consumer, the combination with a stationary plate carrying air tubes secured thereto, of a movable plate mounted thereon, a manifold mounted upon the movable plate, openings in the movable plate corresponding approximately in size to the upper ends of the air tubes, jet tubes mounted upon the movable plate in juxtaposition to the openings therein, air regulating valves secured to the jet tubes above the openings in the movable plate and means for adjusting the height of the air regulating valves above the openings.

45 8. In a smoke consumer, the combination with a stationary plate carrying air tubes secured thereto, of a movable plate mounted thereon, openings in the movable plate corresponding approximately in size to the ends of the air tubes, jet tubes mounted upon the movable plate in juxtaposition to the openings therein, air regulating valves secured to the jet tubes above the openings in the movable plate, and means for sliding the movable plate upon the stationary plate.

55 9. In a smoke consumer, the combination with a stationary plate carrying air tubes secured thereto, of a movable plate mounted thereon, openings in the movable plate corresponding approximately in size to the ends of the air tubes, jet tubes mounted upon the movable plate in juxtaposition to the openings therein, air regulating valves secured to the jet tubes above the openings in the movable plate, means for sliding the movable plate upon the stationary plate,

and means for adjusting the position of the air valves.

10. In a smoke consumer, the combination with a stationary plate carrying air tubes secured thereto, of a movable plate corresponding approximately in size to the adjacent ends of the air tubes, jet tubes mounted upon the movable plate in juxtaposition to the openings therein, air regulating valves secured to the jet tubes above the openings in the movable plate, and a lever fulcrumed near one end of the movable plate and having one end connected to the movable plate by a suitable link.

15 11. In a smoke consumer, the combination with air passages leading into the fire chamber of a furnace or fire box, of a movable plate mounted adjacent to the outer ends of the air passages having openings corresponding approximately in size to the air passages, and air regulating valves suitably mounted near the entrances to the air passages.

20 12. In a smoke consumer, the combination with air passages leading into the fire chamber of a furnace or fire box, of a movable plate mounted adjacent the outer ends of the air passages having openings corresponding approximately in size to the air passages, air regulating valves suitably mounted near the entrances to the air passages, and means for adjusting the air regulating valves relatively to the openings in the movable plate.

25 13. In a smoke consumer, the combination with air passages leading into the fire chamber of a furnace or fire box, of a movable plate mounted adjacent the outer ends of the air passages having openings corresponding approximately in size to the air passages, air regulating valves adjustably mounted near the entrances to the air passages, and means for adjusting the air regulating valves relatively to the openings in the movable plate.

30 14. In a smoke consumer, the combination with air passages leading into the fire chamber of a furnace or fire box, of a movable plate slidingly mounted adjacent the outer ends of the air passages, a manifold secured thereto, openings in the movable plate corresponding approximately in size to the air passages, and air regulating valves suitably mounted near the entrances to the air passages.

35 15. In a smoke consumer, the combination with air passages leading into the fire chamber of a furnace or fire box, of a movable plate slidingly mounted adjacent the outer ends of the air passages and having a manifold secured thereto and having openings corresponding approximately in size to the air passages, and air regulating valves suitably mounted upon jet tubes secured to the movable plate adjacent the openings therein.

40 16. In a smoke consumer, the combination

with air passages leading into the fire chamber of a furnace or fire box, of a movable plate slidingly mounted adjacent the outer ends of the air passages and having a manifold secured thereto and having openings corresponding approximately in size to the air passages, and air regulating valves

mounted upon jet tubes secured to the manifold adjacent the openings in the movable plate.

10

In testimony whereof I affix my signature.

FRANK H. DILLON.
